TELEGRAPH TRANSMITTER

Albert H. Reiber, Evanston, Ill., assignor to Teletype Corporation, Chicago, Ill., a corporation of Delaware

Application March 13, 1942, Serial No. 434,554

20 Claims. (Cl. 178—17)

This invention pertains to printing telegraph systems and apparatus and more particularly to transmitters for sending monopulse isochronous code signals.

The principal object of the invention is to provide a transmitting arrangement for automatically sending standard or fixed messages.

Another object of the invention is to provide a monopulse transmitting system combining a keyboard transmitter and automatic means for transmitting standard or predetermined phrases.

In accordance with the present invention, a keyboard transmitter of the type exemplified by U. S. Patent No. 2,173,147 issued September 19, 1939 to W. J. Zenner is utilized to send the address portion or changeable portion of a message, and a brush type distributor arrangement is employed to send certain predetermined fixed or standard phrases to be incorporated in a complete message to be transmitted. After the changeable portion of the message has been transmitted by the keyboard transmitter, a special key identifying the standard phrase is operated, whereupon transmission proceeds automatically under the control of the brush type distributor and the progress switches, associated with the standard message, to transmit monopulse code signals over the line until the standard phrase transmission has been completed, after which the keyboard transmitter, if the message is not concluded, is again operated for its remainder or closing portion of the message.

More specifically, the principle involved in the adaptation of a brush-type distributor to monopulse isochronous code signal transmission is that when the brush arm leaves the stop segment, the line current becomes zero, thus initiating the no-current or spacing portion of the monopulse code signal. Then, when the brush reaches the conditioned or energized segment corresponding to the character to be printed, an impulse is generated which energizes a magnet which locks up, and in locking up it controls continuous current on the signal line for the remainder of the revolution of the brush, thus providing the marking current portion of the monopulse code signal, irrespective of the condition of the remaining segments on the distributor. Moreover, the sequence of the characters making up the word in a standard phrase is governed by a multiple contact relay interposed between a stepping or progress switch and the segments of the brush type distributor, a relay being allotted to each standard phrase.

A more complete understanding of the forego-

ing objects and features of the invention may be had from the following description when taken in conjunction with the accompanying drawings, wherein like reference characters indicate the same parts throughout, and wherein,

Fig. 1 represents a schematic circuit having embodied therein the principles of the present invention;

Fig. 2 is a graphical representation of a signal 10 of the monopulse type employed in operating printers of the class disclosed in U. S. Patent No. 2,147,075 issued February 14, 1939, to W. J. Zenner; and

Fig. 3 is a schematic circuit of another form 15 of the present invention.

Monopulse signals may be composed of current and no-current signal conditions, and as may be understood by referring to Fig. 2, the transmission of monopulse signals of the type contemplated involves the interruption of a normal line condition for a measured interval which is initiated at a point definite with respect to each transmission cycle and is continued until the distributor has attained a position in the cycle which 20 corresponds to and is identified with the particular character transmitted. At the termination of this impulse, normal line current condition is restored as indicated at the character W in Fig. 2. Normal line current is maintained thereafter 25 until the arrival of the succeeding start instant, when, if a succeeding character is in readiness for transmission, another line interruption is thereat repeated. The alternative (normal and character impulses) line conditions may, if preferred, be comprised of positive and negative signals, or they may be comprised of either polarity of current as one line condition with no current as the alternative line condition. Variations of signaling practice along these lines would not be inconsistent with the structural principles disclosed in the present invention.

It is at times desirable to facilitate the transmission of information containing or embracing general statements or words, and therefore, to 45 simplify this practice, this invention contemplates the provision of means for introducing such standard or general phrases into the transmitted messages. Thus, if it is desired to send the following message "Mr. Fox—wanted on the phone," the name "Mr. Fox" will be transmitted over the line by operating a keyboard transmitting device 11 of the type shown in U. S. Patent No. 2,173,147, after which a key 12 is depressed, which initiates the transmission of the fixed or standard phrase "wanted on the phone" through the instrumen-

tality of a control unit 13 and a brush-type distributor indicated generally as 14. The keys 12 and 15 may constitute two keys of a bank of keys which may be arranged adjacent to the keyboard device 11. Each of the keys of said bank of keys is allotted to a standard word or phrase. For example, key 15 may relate to the phrase "please call your office" and be connected to the unit 16, the operation of which initiates the transmission of the fixed phrase assigned to that key. The system according to the present invention is also adapted to automobile parking and call systems, wherein the license numbers constitute the variable or changeable information to be transmitted by the keyboard device 11, and the name of the make of the automobile constitutes the fixed information to be transmitted under the control of units corresponding to units 13 and 16.

The units 13 and 16 are representative of a group of units for controlling the transmission of standard phrases, and accordingly only the units 13 and 16 of the present embodiment will be herein described in detail.

The unit 13 contains a step-by-step or progress switch which comprises an arcuate series of contacts 17 and a corresponding series of contacts 18, and a pair of contacting arms 19 and 21 mounted on a shaft 22. Also mounted on shaft 22 is a stepping ratchet wheel 23 which cooperates with a pawl 24 pivotally carried on an armature 25 of a stepping magnet 26. Contacts 18 of the progress switch are connected serially in the order of sequence of characters and word spaces in the fixed message or phrase to the segments 27 of ring 28 of distributor 14. For example, contact 18 allotted to the first letter "W" of the first word of the fixed phrase is connected by conductors 29 and 31 to the segment 30 of ring 28 allotted to said character, the conductors 29 and 31 being connected in series with a contact 32 of a gang relay 33. The conductor 31 extends through a cable 34, as do all the conductors similar to conductor 31. Gang relay 33 comprises an electromagnet 35 having a plurality of contacts 32 of a number at least equal to the number of characters and word spaces in the standard phrase assigned thereto. In addition to the plurality of contacts 32, the gang relay 33 is provided with a contact 30 which is effective, as will hereinafter appear, to control the circuit for the stepping magnet 26 of its associated progress switch.

The distributor 14 comprises in addition to the segmented ring 28, the solid rings 36, 37, and 38 and the segmented rings 39 and 41. Distributor 14 is also provided with a brush arm 42 carrying brushes 43 to 48, inclusive. Brushes 43 and 44 cooperate with rings 28 and 36, respectively, and are connected by a conductor 49, brushes 45 and 46 cooperate with rings 37 and 39, respectively, and are connected by a conductor 51, brushes 47 and 48 cooperate with rings 38 and 41, respectively, and are interconnected by a conductor 52, and brush arm 42 cooperates with the armature 53 of a stop magnet 54. The ring 28 is provided with a stop segment 55 which is normally connected to battery as shown, and a start segment 56 to which no current is applied.

Ring 36 of distributor 14 is connected by conductor 57 to a magnet 58. Conductor 57 also has a juncture with a conductor 59 for a purpose which will hereinafter be described. Ring 37 of distributor 14 is connected to battery as shown, and the lower portion of segmented ring 39 is connected by a conductor 61 to the armature 62

of magnet 58. Armature 62 cooperates through contact 63 with the winding of magnet 58 and also with the conductor 59. Ring 38 is connected by conductors 64, 65, and 69, and the afore-mentioned contact 30 of gang relay 33 to the winding of the stepping magnet 26 of the progress switch contained in unit 13. The lower segment of ring 41 is connected by a conductor 66 to the first contact 67 of the series of contacts 17 of the progress switch shown in unit 13. Stop magnet 54 associated with the brush distributor is connected by a conductor 68 to the conductor 66.

The contacts 17, included in the standard phrase or word identified with the particular unit 13, are connected serially by a conductor 69, and the last contact in the word or phrase is connected by a conductor 71 to the winding of the gang relay 35. The conductor 69 is shown in Fig. 1 as being connected to only those contacts 17 embraced in the word "wanted." This is solely for the purpose of illustrating the present invention, it being understood that all of the contacts embraced in the entire standard or fixed phrase; for example, "wanted on the phone," are serially connected by the conductor 69. The unused contacts 17 are connected serially by a conductor 72, and the last contact of this unused series is connected by a conductor 73 to a normally closed contact 74 which is connected to the conductor 68. Armature 25 of magnet 26 is provided with an extension adapted to operate the contact 74 upon energization of the magnet 26 as will presently appear.

General operation

In its stop or unoperated condition, the stop magnet 54 of distributor 14 is unenergized and hence the stop arm 53 is spring held in its clockwise position to block the movement of brush arm 42 and to hold the brush 43 in contactual engagement with stop segment 55 of ring 28. In this position of brush arm 42, current is applied to the signal line from battery, through stop segment 55, through brush 43, over conductor 49, through brush 44, over ring 36, over conductors 57 and 59, through contact 75 (which is analogous to contact 86 of the keyboard transmitter disclosed in the afore-mentioned Patent No. 2,173,147), then over the signal line to the receiver 76 (which may be a printer of the type shown in U. S. Patent No. 2,147,075), thence to ground. Such a condition of the signaling line is the normal, idling condition of a telegraph line wherein the condition is said to be marking; that is, current on the line. In this condition, the magnet 58 remains energized over the afore-described circuit up to and including the conductor 57, from thence the current divides and extends through the winding of the magnet 58 to ground, thereby causing the armature 62 to be attracted to close the contact 63, which at this time however, has no effect, but the purpose of which will be later explained in detail.

Assuming that the following message is to be transmitted, namely, "Mr. Fox, wanted on the phone," the operator will operate the keyboard transmitter 11 to transmit over the signaling line to the receiver 76 the name "Mr. Fox." Following the operation of the keyboard 11 in this manner, the operator turns to the special bank of keys, including keys 12 and 15, and operates key 12. The operation of key 12 effects the closing of contact 71 to complete an energizing circuit for the stepping magnet 26, which circuit, as seen from the drawings, is an obvious one. The

effect of energizing magnet 26 is to attract the armature 25 and to move the pawl 24 leftwardly (as viewed in Fig. 1) to pick up the next tooth on the ratchet wheel 23. Then, when the key 12 is released by the operator, the current of the stepping magnet 26 is cut off, thereby permitting spring 78 to bias the armature 25 clockwise, and to move the pawl 24 to the right to step the ratchet wheel 23 clockwise to bring the contact arms 19 and 21 on shaft 22 into their first operating position in engagement with contacts 67 and 79, respectively.

When contact arm 19 is brought into engagement with segment 67, a circuit is completed for the start magnet 54 of the distributor 14 from battery, through shaft 22, over contacting arm 19, through contact 67, over conductors 66 and 68, thence through the winding of magnet 54 to ground, as a result of which magnet 54 is energized so as to attract its armature 53 to thereby effect its disassociation from the brush arm 42, thus permitting the brush arm 42 to rotate through the instrumentality of a friction clutch (not shown) as is customary in such distributing devices. Also, substantially simultaneously with this action, a circuit is completed for the gang relay magnet 35 from battery, through shaft 22, over contacting arm 19, through contact 67, over conductors 69 and 71, thence through the winding of magnet 35 to ground. At the same time as contacting arm is stepped onto the contact 67, the contacting arm 21 is also stepped onto the contact 79 which, in the present embodiment is representative of the character "W" which is the first character of the first word of the fixed or standard phrase to be transmitted. A circuit then is prepared from battery, over shaft 22 and contacting arm 21, through contact 79, over conductor 29, through contact 32 (now closed), thence over conductor 31 (which extends through cable 34) to the segment W on the ring 28 of the distributor 14. The energization of magnet 35 of the gang relay 33 caused all of the contacts 32 thereof to close, thus closing at contact 32 the portion of the afore-mentioned circuit which extends from the contact 79 to the segment W on the ring 28. Also, contact 30 is closed at this time to prepare a circuit, hereinafter described, for the energization of stepping magnet 26 of the progress switch of unit 13.

Thus, as the brush arm 42 begins to rotate, the marking condition obtains in the signal line until the brush 43 leaves the segment 55 and passes onto the blank or unenergized segment 56, which is commonly known as the start segment. When the brush arm 42 leaves segment 55, the current in the signaling line is removed and the line is said to be in a spacing or no-current condition, and the magnet 53 is thus de-energized and the armature thereof is released, thereby opening contact 63, the function of which will herein-after appear. Also, the selector magnet in the receiving printer 16 is de-energized, thus permitting the rotation of its type wheel as described in the afore-mentioned Patent No. 2,147,075. The spacing condition of the signaling line thus continues as the brush arm proceeds to rotate across the start segment 56 and segments 27 of ring 28, none of which is energized except the segment W, previously described as being in a prepared circuit. Then, when the brush 43 of the brush arm 42 engages segment W on the ring 28, the afore-mentioned circuit which was prepared through the contact 79 and over the con-

ductor 31 is completed through brush 43, over conductor 49, through brush 44, over distributor ring 36, thence over conductors 57, and 59, through contact 75 and over the signaling line to the receiving magnet of the receiving printer 16.

As described in the afore-mentioned Patent No. 2,147,075, the selecting magnet in the receiving printer will at this time become energized to effect printing of the character, at which time 10 the type wheel will be rotated to present the character W thereon to the printing point. Also at this time, the afore-mentioned circuit which was traced through the segment W and over ring 36 will also be completed through the magnet 58 15 which will be energized to attract its armature 62 and close its contact 63 thus locking up the magnet 58 in a circuit extending from battery, over distributor ring 37, through brush 45, over conductor 51, through brush 46, thence through the lower portion of distributor ring 39, over conductor 61, through armature 62 and contact 63, thence through the winding of magnet 58 to ground. The magnet 58 is therefore locked up, and as the brush 43 passes off the segment W, 20 and breaks the circuit through the contact 79 and segment W, marking current will remain on the line through the instrumentality of closed contact 63 under the control of the magnet 58. The signaling line thus remains in an energized condition as the brush arm 42 continues its rotation back to the stop segment 55 in readiness to initiate another rotation for the transmission of a succeeding character.

Referring to Fig. 2 which illustrates graphically a monopulse isochronous code signal, the various conditions obtaining during the transmission of the code signal can now be readily understood from a review of the previously described rotation of the distributor arm 42. For example, the graphical representation above the line indicates marking current, and the representation below the line indicates no-current or spacing current. Thus, as viewed in Fig. 2, the normal condition of the signaling line is marking (i. e., current on the line) and as the magnet 53 is energized and the brush arm begins its rotation, a start condition (which is no-current or spacing) obtains on the line, and this condition continues until the brush arm reaches 40 the segment representative of the character W, which condition is represented in Fig. 2 by the shaded portion below the center line X—X, and indicates the continuance of a spacing or no-current condition until the character W is 45 reached, whereupon the signaling line is again energized with marking current as indicated by the shaded portion above the line X—X, which shaded portion continues as graphically shown until the stop condition is again reached at the 50 end of the code signal interval. The marking condition of the signal from W to the end of the signal which is the stop condition is obtained over the distributor ring 37, as previously described, by virtue of the locking up of the magnet 58.

As the brushes 43 and 46 leave segments 28 and 40 of ring 39, respectively, the brush 46 will, when the brush 43 rests on the stop segment 55, rest on the blank segment 51 of ring 39, whereby the current for magnet 58 is no longer obtained 55 through the rings 37 and 39, but only through the stop segment 55 and ring 36. It is understood that brush 43 must contact segment 55 by the time brush 46 leaves segment 40.

During the complete rotation of the brush arm 75 42, not only was the monopulse code signal for

the character "W" transmitted, but also, a condition was set up for stepping the progress switch to its next contact preparatory to transmitting the second character "A" of the first word "Wanted" of the standard phrase. Thus, as the brush arm travels approximately two-thirds or three-fourths of its cycle of rotation, its brush 48 encounters the lower or energized segment of the ring 41 so that a circuit was completed for the energization of stepping magnet 26 from battery, through shaft 22, over contacting arm 19, through contact 67, thence over conductor 66, through ring 41, then through brush 48, over conductor 52, through brush 47, over ring 38, then over conductors 64 and 65, through contact 30 (now closed), over conductor 69 and through the winding of magnet 26 to ground. The stepping magnet 26 is thus energized to attract its armature 25 and to operate its pawl 24 leftwardly to pick up the next tooth on the ratchet wheel 23. Then, when the brush arm 42 reaches the stop position wherein the brush 43 thereof is in engagement with the stop segment 55, the brush 48 is in contact with the blank or unenergized portion 82 of the ring 41, thus causing the afore-described energizing circuit for magnet 26 to be held open and the magnet 26 to thus become de-energized to permit its armature 25 to be moved rightwardly by spring 78, so that the pawl 24 will rotate the ratchet wheel 23 one step in a clockwise direction, thus bringing the contacting arms 19 and 21 into contact with the next contacts 83 and 84, respectively.

Due to the manner in which the contacts 67 and 83 of the series of contacts 17 are serially connected, the energizing circuit for the stop magnet 54 of the transmitting distributor 14 will remain energized, thereby permitting brush 42 to continue its rotation. The contacting arm 21 now engages the segment 84, which is indicative of the second character "A" of the first word of the standard or fixed phrase to be transmitted. A circuit is then completed from battery through shaft 22, over contacting arm 21, through contact 84, over conductor 85, through contact 86 (now closed), thence over conductor 87 (which extends through the cable 34) to the segment A of the series of segments 27 of the ring 28. Simultaneously with the stepping of the contacting arm 21 into engagement with the contact 84, the gang relay magnet 35 remains energized due to the fact that the contacting portions of contact arms 19 and 21 are sufficiently wide to span or bridge consecutive contacts so that the circuits for the various relays controlled thereby are maintained during the stepping operation. The contacts 17, which include contacts 67 and 83, are serially connected so that the circuit over the conductor 79 substantially is not broken until the completion of the standard phrase or word of the message; therefore, contact 86 associated with the gang relay is closed at this time. As the brush arm 42 continues in its rotation, it will pass off the stop segment 55 and onto the start segment 56, thus breaking the current in the signaling line as heretofore, and initiating the start or no-current portion of the monopulse code signal as indicated in Fig. 2. However, in this instance, the movement of the brush 43 of brush arm 42 onto the first segment 27, which is the "A" segment of the ring 28, will cause current to be applied to the signaling line. For this particular signal, the no-current portion of the code signal is very short inasmuch as "A" is the first segment of the ring. Marking current is applied to the

ring 36 of the distributor 14 as soon as the brush 43 engages the segment indicative of the character "A," whereupon the afore-described circuit through the segment 84 and over conductor 87 is completed through the ring 36, over conductors 57 and 59, through the contact 75, over the signaling line and through the winding of the selector magnet of the receiving printer 76 to ground, thereby causing the printing of the character A, as described in the afore-mentioned Patent No. 2,147,075. Since the segment 81 is only as long as the combined segments 55 and 56, the brush 46 will engage the energized portion of ring 39 at the time that the brush 43 engages the contact or segment indicative of the character A on the ring 28, so that the magnet 58 will become energized and will lock up over the afore-described locking circuit, thus applying and maintaining marking current on the signaling line for the duration of the signal from the point marked letter A in Fig. 2 to the stop terminus of the signal. As the brushes 47 and 48 bridge the lower segment of the ring 41, current is again applied to the stepping magnet 26 over the afore-described circuit therefor. This series of operations is continued for each character of the standard phrase or message. To initiate the transmission of a space signal for word spacing, a circuit is completed through segment 83 which is analogous to the circuits previously described including contacts 79 and 84 and the other segments of ring 28.

After the standard word or phrase has been transmitted, an arrangement has been provided in the present invention for stepping the contacting arms 19 and 21 rapidly back to the position shown in Fig. 1 which is the normal stop position, whereat the contacting arms 19 and 21 rest on blank or unenergized contacts 17 and 18, respectively. Although, for the present description, only one word of the standard phrase has been shown, it is understood that any number of the contacts 17 and 18 may be assigned to the message, and therefore the remaining contacts 17 to be rapidly traversed to the beginning or normal position will be the difference between the number of contacts employed in the message and the total number of contacts in the progress switch. It is, of course, understood that the progress switch would contain sufficient contacts to embrace the longest standard phrase desired, and that the conductor 69 would embrace consecutively all the characters and word spaces of the standard phrase instead of only a single word thereof (which, of course, is shown in Fig. 1 only by way of illustration). Therefore, by way of illustration, the remaining contacts 17, to the left of the contacts serially connected by the conductor 69, are also serially connected by the conductor 72, so that when the contacting arm 19 engages the first of the latter serially connected contacts 17, namely, 89, a buzzer action is started in magnet 26 to return the contacting arms 19 and 21 to their beginning of line position.

As the contacting arm 19 engages the contact 89, a circuit is completed from battery, through shaft 22, over contacting arm 19, through contact 89, over the conductors 72 and 73, through contact 74, thence through the winding of magnet 26 to ground. The energization of magnet 26 causes its armature 25 to be attracted, and the pawl 24 to be actuated leftwardly to pick up the next tooth of the ratchet wheel 23. At the same time, the armature 25 acts to open the contact 14 to break the circuit just described for

stepping magnet 26, which will become de-energized and permit its spring 78 to actuate its armature 25 to operate pawl 24 to cause ratchet wheel 23 to be stepped clockwise one step. Although contact 74 actually closes before pawl 24 completes its rightward travel, the inertia of the moving armature, and the delay in the building up of the magnetic field in magnet 26 are sufficient to permit the completion of this motion and insure reliable step-by-step advancement of the ratchet wheel 23. Thus, the contacting arm 19 is rotated one step so as to engage the contact next succeeding the contact 89 in a clockwise direction, as viewed in Fig. 1, whereupon the circuit for the stepping magnet 26 is again completed over the afore-described circuit including contact 17, conductor 72 and 73, contact 74 (now closed) to again energize magnet 26, whereupon the same action is imparted to the pawl 24 and to the ratchet wheel 23, and the contact 74 is again opened to break the energizing circuit for 26.

This action continues for the remainder of the contacts 17, so that through this buzzer action the contacting arms 19 and 21 are rapidly rotated back to their normal position shown in Fig. 1.

When the contacting arm 19 leaves those contacts 17 which are connected serially by conductor 69, the circuit for the stop magnet 54 of the transmitting distributor 14 is broken thus causing the lock magnet 54 to become de-energized and permitting its armature 53 to fall into the path of the brush arm 42, thereby stopping said brush arm 42 with the brush 43 thereof resting on the stop segment 55, whereupon marking current is again applied to the signaling line through the ring 36 and the conductors 57 and 59 as previously described.

The operation of the circuit hereinbefore given will be exactly the same if the key 15 were to be operated for transmitting the standard phrase identified with the unit 16. Any number of units 13 and 16 may be connected through the cables 34 and 91 to accommodate any number of standard phrases or words, and a corresponding number of keys 12 and 15 being provided in a bank of special keys adjacent the keyboard transmitter 11.

Modification

Having reference to Fig. 3, there is shown another form of the present invention wherein a single progress switch is provided which controls a plurality of gang relays. A single gang relay is provided for each standard phrase or message and is comparable to the units 13 and 16 in Fig. 1. The progress or step-by-step switch in Fig. 3 comprises an arcuate series of contacts 101 and a corresponding series of contacts 102, and a pair of contacting arms 103 and 104 mounted on a shaft 105. Also mounted on shaft 105 is a stepping ratchet wheel 106 which cooperates with a pawl 107 pivotally carried on an armature 108 of a stepping magnet 109. The arcuate series of contacts 101 includes a pair of dead contacts 111 and 112, the remaining contacts 101 being connected serially.

The arcuate series of contacts 102 include a pair of dead contacts 113 and 114, the remaining contacts 102 being connected to the contacts of a plurality of gang relays, four of which are shown in Fig. 3, and numbered 115, 116, 117, and 118. The contacts of the gang relays 115 to 118 are also connected to conductors which

extend through a cable 119 and terminate at segments of a segmented ring 121 of a brush type distributor indicated generally as 122. Each of the gang relays 115-118 comprises an electromagnet having a plurality of contacts of a minimum number at least one greater than the number of characters and word spaces in the standard phrase represented thereby.

The distributor 122 comprises in addition to the segmented ring 121, the solid rings 123, 124, and 125, and the segmented rings 126, and 127. The distributor 122 is also provided with a brush arm 128 carrying brushes 129 to 135, inclusive. Brushes 129 and 131 cooperate with rings 121 and 123, respectively, and are connected together by a conductor 136. Brushes 132 and 133 cooperate with the rings 124 and 126, respectively, and are connected by a conductor 137. Brushes 134 and 135 cooperate with the rings 125 and 127, respectively, and are interconnected by a conductor 138. The brush arm 128 cooperates with the armature 139 of a stop magnet 141. The ring 121 is provided with a stop segment 142 which is normally connected to battery (as shown), and a start segment 143 to which no current is applied.

Ring 123 is connected by a conductor 144 to a magnet 145. Conductor 144 also has a junction with a conductor 146 which is comparable in purpose to conductor 59 in Fig. 1. Ring 124 is connected to battery (as shown), and the lower portion of ring 126 is connected by a conductor 147 to the armature 148 of magnet 145. Armature 148 cooperates through contacts 149 with the winding of magnet 145 and also with the conductor 146. Ring 125 is connected by conductors 151 and 152 to the winding of the stepping magnet 109 of the progress switch. The lower segment of ring 127 is connected by a conductor 153 to the first contact 154 of the series of contacts 101 of the progress switch. The winding of the distributor stop magnet 141 is connected at one end to ground and at the other end to a conductor 155 which extends to a contact 156 of a control relay 157, the function of which is to control the restoration of the progress switch to its normal rest position automatically, at the completion of transmission of a standard phrase which has been transmitted under the control of one of the gang relays 115, 116, 117, or 118. Contact 158 of the serially connected contacts 101 is connected by a conductor 159 to a contact 161 of the relay 157. Also connected to the conductor 159 are the relays 162 and 163 for controlling the gang relays 115 and 116, respectively. Corresponding relays (not shown) similar to relays 162 and 163 are provided for gang relays 117 and 118. Contacts 164, 165, 166, and 167 of the series of contacts 102 represent end-of-message contacts for the various standard phrases and these contacts are connected through their respective gang relays 115 to 118 to complete an energizing circuit for control relay 157. For example, if the contact 164 is the message-end contact for the standard message or phrase controlled by gang relay 115, then when the contact arm 104 reaches the contact 164, a circuit will be completed from battery, through shaft 105, over contact arm 104, through contact 164, then through contact 168 (which will have been closed due to the energization of the magnet 109 of the gang relay 115 in a manner hereinafter described), over conductors 171 and 172, through the winding of relay 157 to ground, thereby initiating the restoration of the system shown in Fig. 3 to a normal begin-

ning-of-message position, in readiness for the transmission of a succeeding standard message or phrase. The manner in which this restoration is achieved will be described in detail hereinafter.

General operation

In its stop or unoperated condition, the stop magnet 141 of distributor 122 is unenergized, and hence the armature 139 is spring held in its clockwise position to block the movement of brush arm 128 and to hold the brush 129 in contactual engagement with the stop segment 142. In this position of brush arm 128, current is applied to the signal line from battery, through stop segment 142, through brush 129, over conductor 136, through brush 131, over ring 123, over conductors 144 and 146, through contact 173 (which is comparable to contact 86 of the keyboard transmitter disclosed in the afore-mentioned Patent No. 2,173,147), then over the signal line to the receiver 174 (which may be a printer of the type shown in the previously mentioned U. S. Patent No. 2,147,075), thence to ground. Such a condition of the signaling line is the normal, idle condition wherein the condition is said to be marking; that is, with current on the line. In this condition, the magnet 145 remains energized over the afore-described circuit up to and including the conductor 144, from whence the current divides and extends through the winding of the magnet 145 to ground, thereby causing the armature 148 to be attracted, to close the contact 149, which at this time, as previously mentioned in connection with Fig. 1, has no effect but its purpose will hereinafter be explained.

Assuming that the following message (which for purpose of comparison will be assumed to be the same as that controlled by the units 13 in Fig. 1) is to be transmitted, namely, "Mr. Fox, wanted on the phone," the operator will operate the keyboard transmitter 175 (of the type shown in U. S. Patent No. 2,173,147), to transmit over the signaling line to the receiver 174 the name "Mr. Fox." Following the operation of the keyboard 175 in this manner, the operator turns to the special bank of keys, including keys 176, 177, and 178. As described in connection with Fig. 1, the keys 176, 177, and 178 constitute three keys of a bank of keys which may be arranged adjacent to the keyboard device 175. The key 176, in the present embodiment, is identified as the start key and is operated to initiate the transmission of every standard phrase or message. Each of the other keys 177 and 178 (which are two of a plurality of keys equal in number to the number of gang relays 115 to 118 which correspond to special or standard phrases to be transmitted) of said bank of keys is allotted to a standard word or phrase; for instance, key 177 may be associated with the standard phrase "Wanted on the phone," and key 178 may be identified with the standard phrase "Please call your office." Thus, key 177 is connected to the gang relay 115 allotted to the phrase "Wanted on the phone," and the operation of this key initiates the transmission of the fixed phrase assigned thereto. With the modification shown in Fig. 3, it is necessary to operate and release the start key 176 while holding any one of the other keys 177 and 178 down.

The operation of keys 176 and 177 in this manner will result in the following operations: The operation of key 176 effects the closing of contact 179 to complete an energizing circuit for the stepping magnet 109 which circuit, as seen from Fig.

3, extends from battery connected to the key 176 through contact 179 and winding of magnet 109 to ground. The effect of energizing magnet 109 is to attract the armature 108 and to move the pawl 107 leftwardly (as viewed in Fig. 3) to pick up the next tooth on the ratchet wheel 106. Thence, when the key 176 is released by the operator, the current of the stepping magnet 109 is cut off thereby permitting spring 181 to bias the armature 108 clockwise, and to move the pawl 107 to the right to step the ratchet wheel 106 clockwise to bring the contact arms 103 and 104 on shaft 105 into engagement with contacts 182 and 183, respectively.

This last operation brings contact arm 103 into engagement with contact 182 and a circuit is completed for the start magnet 141 of the distributor 122 from battery, through shaft 105, over contacting arm 103, through contact 182, over conductors 153 and 184, thence through armature 185 and contact 156, over conductor 155, and thence through the winding of magnet 141 to ground, as a result of which magnet 141 is energized so as to attract its armature 139 and to effect its disassociation from the brush arm 128, thus permitting the brush arm 128 to rotate through the instrumentality of a friction clutch (not shown) as is customary in such distributing devices. At the same time, a circuit is also completed from battery, through shaft 105, over contact arm 103, through contact 182, over conductor 186 (serially connecting the contacts 101), then through contact 158, over conductor 159, over conductor 187, thence through the winding of relay 162, through contact 188, over armature 189, then through the winding of gang relay 169 to ground. The gang relay 169 will then become energized to pull up its armature to close all of its contacts. As the contacting arm 103 is stepped onto the contact 182, the contacting arm 104 is simultaneously stepped onto the contact 183 which, in the present instance, is representative of the character "W" which is the first character of the first word "Wanted" of the fixed or standard phrase (selected for this description) to be transmitted. A circuit is now prepared from battery over shaft 105 and the contacting arm 104, through contact 183, over conductor 191, through contact 192 (now closed), thence over conductor 193 (which extends through cable 119) to the segment "W" on the ring 121 of the distributor 122. It is to be observed that the operation of the gang relay 115 is effected substantially simultaneously with the stepping of the contact arm 104 onto the segment 183. Therefore, as previously described, the energization of magnet 169 of the gang relay 115 causes all of the contacts associated therewith to close, thus closing at contact 192 the portion of the afore-mentioned circuit which extends from the contact 183 to the segment "W" on the ring 121.

As the brush arm 128 begins to rotate, the marking condition continues in the signal line until the brush 129 leaves its stop segment 142 and passes onto the blank segment 143, which is commonly known as the start segment. When the brush 129 leaves segment 142, the current in the signaling line is removed and the line is said to be in the spacing or no-current condition. The magnet 145 is thus de-energized and the armature thereof is released, thereby opening contact 149. Also, the selector magnet in the receiving printer 174 is de-energized thus permitting the rotation of its type wheel as described in the afore-mentioned Patent No. 2,147,075. The spacing

ing condition of the signaling line thus continues as the brush arm proceeds to rotate across the start segment 143 and segments 194 of the segmented ring 121, none of which is energized except the segment "W," previously described as being in a prepared circuit. Then, when the brush 129 of the brush arm 128 engages segment "W" on ring 121, the afore-mentioned circuit, which was prepared through the contact 183 and over the conductor 193, is completed through brush 129, over conductor 136, through brush 131, over distributor ring 123, thence over conductors 144 and 146, through contact 173, and over the signaling line to the receiving magnet of the receiving printer 174.

As described in the afore-mentioned Patent No. 2,147,075, the receiving magnet of the printer will at this time become energized to effect printing of the character, at which time the type wheel will have rotated to present the character "W" thereon to the printing point. Also at this time, the afore-mentioned circuit which was traced through the segment "W" and over ring 123 will also be completed through the magnet 145 which will be energized to attract its armature 148 and close its contact 149, thus locking up the magnet 145 over a circuit extending from battery, over ring 124, through brush 132, over conductor 137, thence through brush 133, and over ring 126, over conductor 147, through armature 148 and contact 149, thence through the winding of magnet 145 to ground. The magnet 145 is therefore locked up, and as the brush 129 passes off the segment "W," thus breaking the circuit through the contacts 123 and segment "W," marking current will remain on the line through the instrumentality of closed contact 149 under the control of the magnet 145. The signaling line thus remains in an energized or marking condition as the brush arm 128 continues its rotation back to the stop segment 142 in readiness to initiate another rotation for the transmission of a succeeding character.

As the brushes 129 and 123 leave segments 121 and 126, respectively, the brush 133 will, when the brush 129 rests on the stop segment 142, rest on the blank segment 195 of ring 126, whereby the current for magnet 145 is no longer obtained through the rings 124 and 126, but only through the stop segment 142 and ring 123. It is understood, of course, that brush 129 must contact segment 142 by the time brush 133 leaves the segment 126.

During the complete rotation of the brush arm 128, not only was the monopulse code signal for the character "W" transmitted, but also a condition was set up for stepping the progress switch to its next contact preparatory to transmitting the second character "A" of the first word of the standard phrase. Thus, as the brush arm traveled approximately two-thirds or three-fourths of its cycle of rotation, its brush 135 encountered the lower or energized segment of the ring 127 so that a circuit was completed for the energization of stepping magnet 109 from battery, through shaft 165, over contacting arm 103, through contact 182, then over conductor 153, through ring 127, then through brush 135, over conductor 133, through brush 134, over ring 125, then over conductors 151 and 152 and through 70 the winding of the magnet 109 to ground. The stepping magnet 109 is thus energized to attract its armature 108 and to operate its pawl 107 leftwardly to pick up the next tooth on the ratchet wheel 106. Thus, when the brush arm 128 reach-

es the stop position wherein the brush 129 thereof is in engagement with the stop segment 142, the brush 135 is in contact with the blank or un-energized portion 196 of the ring 127, thus causing the afore-described energizing circuit for magnet 109 to be held open and the magnet 109 to thus become de-energized to permit its armature 108 to be moved rightwardly by spring 181, so that the pawl 107 will rotate the ratchet wheel 106, one step in a clockwise direction, thus bringing the contacting arms 103 and 104 into contact with the next contacts 197 and 198, respectively. Due to the manner in which the contacts 101 are serially connected, the energizing circuit for 15 the stop magnet 141 of the transmitting distributor 122 will remain energized, thereby permitting the brushes of the distributor to continue their rotation. The contacting arm 104 now engages the segment 198 which is indicative of the 20 second character "A" of the first word of the standard phrase to be transmitted. A circuit is then completed from battery through shaft 105, over contacting arm 104, through contact 198, over conductor 199, through contact 201 (now closed), thence over conductor 202 (which extends through the cable 119) to the segment "A" 25 of the series of segments 194 of the ring 121. The gang relay 169 remains locked up over the aforementioned circuit extending from battery 30 through shaft 105, contact arm 103, conductor 186, conductors 159 and 187, winding of magnet 162, contact 188 and armature 189, and winding of the relay 169 to ground. The transmission of 35 the monopulse code signal identified with the character "A" will be effected in the same manner as was described in the embodiment as exemplified in Fig. 1. As the brushes 134 and 135 encounter the lower portion of the ring 127, current is again applied to the stepping magnet 109 40 over the aforescribed circuit therefor. This series of operations is continued for each character and space of the standard phrase or message.

After the standard word or phrase has been 45 transmitted, the contacting arms 103 and 104 are stepped rapidly back to the position shown in Fig. 2, which is the normal stop position. At the conclusion of each standard message, there is a 50 contact; for example contact 164 identified with the present described message, which, when contacted by the arm 104 will complete a circuit for the energization of the control relay 157, from battery, over arm 104, through contact 164, through contact 163 (now closed), over conductor 171 and 172, through the winding of relay 157 to ground. The energization of magnet or relay 157 will cause the armatures 185 and 202 there- 55 of to be attracted, thus closing contacts 205 and 161, respectively. Relay 157 will become locked up over a circuit from ground, through the winding of relay 157, through contact 205, over armature 185, over conductors 184 and 153, contact 154, over conductor 186, through contacting arm 103 (as it traverses the serially connected contacts 101), thence to battery. Another stepping 60 circuit for magnet 109 will be completed from battery, through contact arm 102, over contacts 101 and conductor 188, contact 158, over conductor 159, through contact 161, over armature 204, thence over conductor 205, over armature 206, over conductor 152, and through the winding of magnet 109 to ground. Magnet 109 will become 65 energized and pull up its armature 108 to advance energized and pull up its armature 108 to advance 75 the pawl 107 to pick up another tooth on

the ratchet 106. However, by the same action, the armature 108 will act upon contact lever 206 to open contact 207, thus breaking the energizing circuit for the magnet 109, whereupon armature 108 will be released by spring 181, permitting contact 206 to close, whereupon the energizing circuit for magnet 109 through contact 161 of relay 157 will again be completed to repeat the stepping action just described. This interrupting or buzzing action will continue until the contact arms 103 and 104 have reached their respective dead contacts 111 and 113, whereupon the progress switch is thereby restored to its normal position for the initiation of transmission of a new standard phrase upon the depression of one of the contact keys 177, 178, and start key 176. When contact 111 is thus reached, the magnet 157 will become de-energized because of the breaking of the locking circuit therefor, inasmuch as arm 103 will not carry current because contacts 111 and 112 are dead contacts.

The contact 164, which is the message-end contact identified with the previously described message group of contacts controlled by the gang relay 115 and acts through the contact 168 of the gang relay 115 to control the relay 157, may for some longer message be a contact for controlling a specific character of that message. For example, contact 164, besides representing the message-end contact of a standard message such as "wanted on the phone," may be also a character of another message such as "please call your office." In such event, the contact 168 is connected directly to a contact of another gang relay which controls the last-mentioned message; that is, gang relay 116. Accordingly, for the last-mentioned message, the message-end contact might be such as is indicated 166 in Fig. 3, which is connected to a contact 207 in the gang relay 116 and to the winding of the control relay 157. This contact indicated 207 may also be connected to a contact 208 in gang relay 117, and thus the contact 166 may represent not only a message-end signal, but may also represent a character in the message controlled by the gang relay 117, represented by contact 208.

Although the present invention has been disclosed in connection with certain specific embodiments thereof, it is understood that such embodiments are merely illustrative and not restrictive and that all forms coming within the scope of equivalency of the appended claims are intended to be covered by the invention.

What is claimed is:

1. In a signal transmission system, a start-stop rotary distributor comprising a plurality of segments and an itinerant seeker operable thereover, a step-by-step switch, a plural contact relay device, a plurality of circuits each corresponding with one of said segments and embracing a terminal of said switch and a contact in said relay device in predetermined manner, means for preparing said circuits individually under the control of said switch, means for initiating the rotation of said switch, means for producing the character selecting impulse of a monopulse isochronous code signal, means effective upon the traversal of said seeker over the segment of a prepared circuit to establish the definitive impulse of said code signal irrespective of the condition of the segments further traversed, and means under control of said distributor for stepping said switch sequentially to produce through the instrumentality of said relay a predetermined message.

2. In a signal transmission system, a start-stop rotary distributor comprising a plurality of segments and an itinerant seeker operable thereover, a step-by-step switch, a plural contact relay device, a plurality of circuits each corresponding with one of said segments and embracing a terminal of said switch and a contact in said relay device in predetermined manner, means for preparing said circuits individually under the control of said switch, means for initiating the rotation of said switch, means for producing the character selecting impulse of a monopulse isochronous code signal, means effective upon the traversal of said seeker over the segment of a prepared circuit to establish the definitive impulse of said code signal irrespective of the condition of the segments further traversed, and means under control of said distributor for stepping said switch sequentially to produce through the instrumentality of said relay a predetermined message, and means effective automatically following the transmission of said predetermined message to condition said progress switch for reoperation.

3. In a signal transmission system, a start-stop distributor comprising a plurality of segments and an itinerant seeker operable thereover, a progress switch, a plural contact relay device, a plurality of circuits each corresponding with one of said segments and embracing a terminal of said switch and a contact in said relay device in predetermined manner, means for preparing said circuits individually under the control of said switch, means for initiating the rotation of said switch, means for producing the character selecting impulse of a monopulse isochronous code signal, electromagnetic means, means effective upon the traversal of said seeker over the segment of a prepared circuit to operate said electromagnetic means to establish the definitive impulse of said code signal irrespective of the condition of the segments further traversed, and means under control of said distributor for stepping said switch sequentially to produce through the instrumentality of said relay a predetermined message, and means effective automatically following the transmission of said predetermined message to condition said progress switch for reoperation.

4. In a signal transmission system, a start-stop distributor comprising a plurality of segments and an itinerant seeker operable thereover, a progress switch, a plural contact relay device, a plurality of circuits each corresponding with one of said segments and embracing a terminal of said switch and a contact in said relay device in predetermined manner, means for preparing said circuits individually under the control of said switch, means for initiating the rotation of said switch, means for producing the character selecting impulse of a monopulse isochronous code signal, electromagnetic means, means effective upon the traversal of said seeker over the segment of a prepared circuit to operate said electromagnetic means to establish the definitive impulse of said code signal irrespective of the condition of the segments further traversed, and means under control of said distributor for stepping said switch sequentially to produce through the instrumentality of said relay a predetermined message.

5. In a signaling system, a keyboard transmitter having a switch mechanism for operating a transmitting contact in a signal line to generate monopulse isochronous code signals, an auxiliary transmitting means exercising dual control over said signal line comprising means effective under certain operating conditions to effectuate a first

predetermined control of said signal line and means effective under other operating conditions to effectuate a definitive control of said signal line to consummate the generation of monopulse isochronous code signals, and means for controlling the transmission of signals by said auxiliary transmitting means, whereby said transmission is effective through said transmitting contact.

6. In a signaling system, a keyboard transmitter having a switch mechanism for operating a transmitting contact in a signal line to generate monopulse isochronous code signals, an auxiliary transmitting means exercising dual control over said signal line comprising means effective under certain operating conditions to effectuate a first predetermined control of said signal line to produce the character selecting impulse of a monopulse isochronous code signal and means effective under other operating conditions to effectuate a further control of said signal line to establish the definitive impulse of said code signal, and means for controlling the transmission of signals by said auxiliary transmitting means, whereby said transmission is effective through said transmitting contact.

7. In a signaling system, a signal line, a transmitting means exercising dual control over said signal line comprising means effective under certain operating conditions to effectuate a first predetermined control of said signal line to produce the character selecting impulse of a monopulse isochronous code signal and means effective under other operating conditions to effectuate a further control of said signal line to establish the definitive impulse of said code signal, a progress switch, a plural contact relay device, a plurality of circuits each connected between said progress switch and said transmitting means and including a contact of said relay device in accordance with a predetermined message to be transmitted, means for preparing said circuits individually under the control of said switch, means for controlling the establishment of said circuits to effectuate the transmission of monopulse code signals thereover, and means under the control of said transmitting means for stepping said switch sequentially to produce said message.

8. In a signal transmission system, a start-stop distributor comprising a plurality of segments and an itinerant seeker operable thereover, a progress switch, a plurality of multiple-contact relay devices, a plurality of circuits each corresponding with one of said segments and embracing a terminal of said switch and contacts in one or more of said relay devices in predetermined manner, means for preparing said circuits individually under the control of said switch, means for initiating the rotation of said seeker to produce the character selecting impulse of a monopulse isochronous code signal, electromagnetic means, means effective upon the traversal of said seeker over the segment of a prepared circuit to operate said electromagnetic means to establish the definitive impulse of said code signal irrespective of the condition of the segments further traversed, and means under control of said distributor for stepping said switch sequentially to produce through the instrumentality of an operated one of said relays a predetermined message.

9. In a signal transmission system, a start-stop distributor comprising a plurality of segments and an itinerant seeker operable thereover, a progress switch, a plurality of multiple-contact relay devices, a plurality of circuits each

corresponding with one of said segments and embracing a terminal of said switch and contacts in one or more of said relay devices in predetermined manner, means for preparing said circuits individually under the control of said switch, means for initiating the rotation of said seeker to produce the character selecting impulse of a monopulse isochronous code signal, electromagnetic means, means effective upon the traversal of said seeker over the segment of a prepared circuit to operate said electromagnetic means to establish the definitive impulse of said code signal irrespective of the condition of the segments further traversed, means under control of said distributor for stepping said switch sequentially to produce through the instrumentality of an operated one of said relays a predetermined message automatically following the transmission of said predetermined message to condition said progress switch for reoperation.

10. In a signal transmission system, a start-stop rotary distributor comprising a plurality of segments and an itinerant seeker operable thereover, a single step-by-step switch, a plurality of multiple-contact relay devices, a plurality of circuits each corresponding with one of said segments and embracing a terminal of said switch and contacts in one or more of said relay devices in predetermined manner, means for preparing said circuits individually under the control of said switch, means for initiating the rotation of said seeker to produce the character selecting impulse of a monopulse isochronous code signal, means effective upon the traversal of said seeker over the segment of a prepared circuit to establish the definitive impulse of said code signal irrespective of the condition of the segments further traversed, and means under control of said distributor for stepping said switch sequentially to produce through the instrumentality of an operated one of said relays a predetermined message.

11. In a signal transmission system, a start-stop rotary distributor comprising a plurality of segments and an itinerant seeker operable thereover, a single step-by-step switch, a plurality of multiple-contact relay devices, a plurality of circuits each corresponding with one of said segments and embracing a terminal of said switch and contacts in one or more of said relay devices in predetermined manner, means for preparing said circuits individually under the control of said switch, means for initiating the rotation of said seeker to produce the character selecting impulse of a monopulse isochronous code signal, means effective upon the traversal of said seeker over the segment of a prepared circuit to establish the definitive impulse of said code signal irrespective of the condition of the segments further traversed, means under control of said distributor for stepping said switch sequentially to produce through the instrumentality of an operated one of said relays a predetermined message, and means effective automatically following the transmission of said predetermined message to condition said progress switch for reoperation.

12. In a telegraph system, a primary transmitting device for transmitting messages of changeable character, said device comprising a single normally closed line contact and means for generating monopulse isochronous code signals, an auxiliary transmitting device for transmitting a fixed message, said auxiliary device comprising a progress switch and automatic means for defin-

ing monopulse isochronous code signals under the control of said switch, and means for automatically restoring said auxiliary transmitting device to normal at the conclusion of transmission of a fixed message.

13. In a telegraph system, a primary transmitting device, a series of keys for controlling the transmission by said device of messages of a changeable nature in accordance with the keys operated, said device comprising a single normally closed line contact and means for generating a monopulse isochronous code signal upon the actuation of each key, an auxiliary transmitting device for transmitting a fixed message, a series of message keys one allotted to each fixed message, said auxiliary device comprising a progress switch and automatic means responsive to each operation of a message key for defining monopulse isochronous code signals under the control of said switch.

14. In a telegraph system, a primary transmitting device, a series of keys for controlling the transmission by said device of messages of a changeable nature in accordance with the keys operated, said device comprising a single normally closed line contact and means for generating a monopulse isochronous code signal upon the actuation of each key, an auxiliary transmitting device for transmitting a fixed message, a series of message keys one allotted to each fixed message, said auxiliary device comprising a progress switch and automatic means responsive to each operation of a message key for defining monopulse isochronous code signals under the control of said switch, and means for automatically restoring said auxiliary transmitting device to normal at the conclusion of transmission of a fixed message.

15. In a telegraph system, a primary transmitting device, a series of keys for controlling the transmission by said device of messages of a changeable nature in accordance with the keys operated, said device comprising a single normally closed line contact and means for generating a monopulse isochronous code signal upon the actuation of each key, an auxiliary transmitting device for transmitting a fixed message, said auxiliary device comprising a progress switch, a plurality of multiple-contact relay devices, and automatic means for defining monopulse isochronous code signals under the joint control of said switch and said relays.

16. In a telegraph system, a primary transmitting device, a series of keys for controlling the transmission by said device of messages of a changeable nature in accordance with the keys operated, said device comprising a single normally closed line contact and means for generating a monopulse isochronous code signal upon the actuation of each key, an auxiliary transmitting device for transmitting a fixed message, said auxiliary device comprising a progress switch, a

plurality of multiple-contact relay devices, automatic means for defining monopulse isochronous code signals under the joint control of said switch and said relays, and means for automatically restoring said auxiliary transmitting device to normal at the completion of transmission of a fixed message.

17. In a telegraph system, a line conductor, a printing telegraph receiver connected to said line conductor, a primary transmitting device for generating signal impulses for application to said line conductor to operate said receiver according to a variable message, an auxiliary transmitter arranged to generate the same type of signal impulses generated by said primary transmitting devices, and means in said auxiliary transmitter for determining the impulses of any one of a plurality of fixed messages to be transmitted over said line conductor and recorded on said receiver.

18. In a telegraph system, a line conductor, a printing telegraph receiver connected to said line conductor, a primary transmitting device for generating signal impulses for application to said line conductor to operate said receiver according to a variable message, an auxiliary transmitter arranged to generate the same type of signal impulses generated by said primary transmitting devices, and means selectively controlled by an operator for determining the impulses of any one of a plurality of fixed messages to be transmitted by said auxiliary transmitter over said line and recorded on said receiver.

19. In a telegraph system, a line conductor, a printing telegraph receiver connected to said line conductor, a primary transmitting device for generating signal impulses for application to said line conductor to operate said receiver according to a variable message, an auxiliary transmitter arranged to generate the same type of signal impulses generated by said primary transmitting devices, and means selectively controlled by an operator following the operation of the primary transmitter for determining the impulses of any one of a plurality of fixed messages to be transmitted by said auxiliary transmitter over said line and recorded on said receiver following the recording thereby of the variable message.

20. In a telegraph system, a line conductor, a printing telegraph receiver connected to said line conductor, a primary transmitting device for generating signal impulses for application to said line conductor to operate said receiver according to a variable message, an auxiliary transmitter arranged to generate the same type of signal impulses generated by said primary transmitting devices, means individually allocated to fixed messages, and means selectively controlled by an operator to operate said means whereby impulses identifying said particular fixed message will be transmitted by said auxiliary transmitter over said line to effect operation of said receiver.

ALBERT H. REIBER.
